UNITED STATES PATENT OFFICE

HERBERT F. OBERGHELL, OF RIVER FOREST, ILLINOIS, ASSIGNOR, BY MESNE ASSIGNMENTS, TO AUTOMATIC ELECTRIC INC., OF CHICAGO, ILLINOIS, A CORPORATION OF DELAWARE

AUTOMATIC SWITCH

Application filed March 5, 1925. Serial No. 13,046.

This invention relates in general to automatic telephone systems, more especially to improvements in the mechanical design of the switches of such a system.

The invention relates specifically to an improved structure for the non-numerical line switches of an automatic telephone system, and to an improved armature arrangement of such switches and of certain relays in the system. One of the objects of this invention is the design of an improved line switch of the plunger type that permits ease of manufacture and assembly, simplification of the adjustment and maintenance operations.

A further object of this invention is the adaption of the armature arrangement of this line switch to the structure of a horizontal type automatic relay, forming a simplified two-step relay.

Other objects and advantages of this invention will appear from the detailed specification and claims which follow.

Referring to the drawings comprising Figs. 1-9, inclusive, Figs. 1, 2, 3, 8 and 9 are assembly and detail drawings of the line switch structure incorporating the features of this invention. Figs. 5, 6 and 7 are details of the improved armature arrangement of my invention adapted to the horizontal type automatic relay. Fig. 4 shows a part of an automatic telephone circuit incorporating the line switch and relay of this invention.

Referring to the drawings more in detail, Fig. 1 shows the improved switch completely assembled. The well known plunger type line switch, associated with the subscriber's line, is shown in detail in the book "Automatic Telephone Practice," by Harry E. Hershey, in Fig. 27 on plate 2 of the fourth edition. Among the improvements made in this invention over the standard switch as shown in the reference, is the simplification of the heel piece structure of the line relay designated by 2 in Fig. 1. In the old structure the heel piece of the line relay was a separate member attached to the main frame of the line switch by machine screws. In the present invention the heel piece structure 17 has been formed as a part of the main frame 50 of the switch. A further improvement upon

the line relay of the switch is in the armature arrangement, the old switch using a pivot point bearing which is exceedingly difficult to maintain in proper adjustment. The improvement in this invention employs a simpler armature mounting arrangement that remains in adjustment indefinitely with little or no maintenance.

A further improvement in this invention is in regard to the mounting of the main magnet 3 of Fig. 1 of the line switch. In the standard switch of the above reference, the heel piece structure of this magnet was formed L-shaped, with a shorter portion parallel to the base of the main switch-frame, the core being attached to this latter portion. In this invention the heel piece of the main magnet is formed as a straight projection of the main switch-frame, and the core 9 of the magnet extended and attached directly to the frame 70 of the switch.

In the switch of the above reference, a main spring is attached to the base or the right of the operating magnet. This spring bears against a roller on the plunger armature in such a manner as to return the plunger armature to its normal position when the operating magnet is deenergized. In the present invention this main spring 11 has been added to the spring assembly from which 80 position it operates against a lever attached to the plunger armature 4 to return it to its normal position. This arrangement makes possible the use of a make contact operated off this main spring to operate a meter to 85 record the number of times the plunger armature is operated, and results also in a simplified construction of both the switch-frame 1 and plunger armature 4.

The bridge cut-off armature of the standard switch lies inside and beneath the pull-down armature, an arrangement which necessitates a step in the core of the main magnet. The bridge cut-off armature 5 of this invention lies on the inside and above the pull-down 95 armature 4. The bridge cut-off armature is so shaped that a projection on the end of it extends through an opening in the pull-down armature, an arrangement which makes possible the use of an ordinary square end core 100

for the magnet 3. The pull-down armature 4 in addition to being slotted to permit the bridge cut-off armature to work through it is simplified by the rearrangement of the main spring 11 as mentioned above.

In the standard switch of the above reference the jack mounting bracket is a separate member attached to the main switch frame by a screw. In the simplification of this switch 10 in this invention, the jack mounting bracket 18 of Fig. 2 is formed as an integral part of the main switch frame 1.

Fig. 2 shows the new switch frame stripped of attachments. It will be noted that the 15 frame is formed of one piece of metal with the projections bent at right angles from the main body of the frame. The line relay heel piece 17 and the main magnet heel piece 16 are drilled and topped to permit the mounting 20 of their respective armatures and spring assemblies. A projection 19 of the switch frame supports the back stop screw 10 of Fig. 1 against which the plunger armature 4 rests when the plunger 6 is under the control 25 of the guide shaft. A designation card holder 10' is held between the projection 19 and the lock nut on the screw 10.

Fig. 3 shows a detail of the pull-down and bridge cut-off armature mounting, both 30 armatures being supported on the single bearing pin 15 which is in turn supported by the mounting bracket 15' which is attached to the heel piece by two screws.

The plunger 6 of the line switch has been 35 improved as shown in Figs. 1, 8 and 9. A rib 20 has been formed in the neck of the plunger to stiffen the structure. A sectional view of a portion of this neck is shown in detail in Fig. 8.

The upper part of the plunger 6 is bent back forming a flange against which the plunger guide shaft rests when the switch is in its normal position. This flange 21 is formed 45 at an angle slightly more than 90 degrees to the face of the plunger. The angle of this flange causes the plunger to strike the guide shaft on its outside edge, Fig. 9, and the flange bends slightly before coming to rest against the guide shaft. This arrangement absorbs 50 the shock as the plunger returns to normal, thereby relieving the strain on the plunger bearing pin 22 and the guide shaft, not shown. Fig. 9, which is a sectional view of the plunger 55 6 through the axis AA, clearly shows the details of this construction.

Referring to Figs. 5 and 6 the armature arrangement of the line switch shown in Fig. 1 has been adapted to a horizontal type automatic relay. The main armature 204 is pierced at a point adjacent to the core 209 of the relay and the auxiliary armature 205 extended through this opening. The two armatures are supported by the single bearing pin 60 21' which is attached to the heel piece by

means of the mounting bracket 215' in the manner similar to that on the line switch.

Fig. 7 shows the details of the armature lever 204 and bushing 206. The bushing is made of hard rubber and attached to a projection of the armature lever by an eyelet 207, which extends through the armature. This eyelet is made of phosphor bronze and is so shaped that its back portion 207' forms a residual plate, keeping the armature a 75 small distance away from the heel piece when in its normal position.

A further advantage of the armature arrangement of this invention lies in the easy 80 manner in which the armature assembly can be assembled on the switch. When properly assembled, the center of the bearing pin 215 is exactly even with the end of the core 209 and the heel piece 201. In assembling, this adjustment is made by placing the armatures 85 on the heel piece, pushing them into their operated position and then tightening the screws which hold the mounting bracket 215' to the heel piece. This same advantage and method of assembly applies equally well to 90 the line switch structure.

Fig. 4 shows a circuit embodying the switch and relay of this invention. This circuit comprises the primary and secondary line switches of any well known automatic 95 system, such as that shown in the application of T. G. Martin, Serial No. 452,468, filed March 15, 1921. The primary circuit of Fig. 4 is identical with that shown in the reference, but the secondary line switch circuit 100 has been modified by using the two step relay 150 of this invention. Assuming that the subscriber at A desires to initiate a call, he will remove his receiver from the switchhook causing the line relay 2 of his individual line 105 switch C to operate over a circuit traceable from start ground, over conductor 103, through springs 13, line conductor 101, through the telephone, to line conductor 102, through springs 12, through the winding of 110 relay 2 to grounded negative battery. Relay 2 energizes over this circuit and at springs 14 closes a circuit for the pull-down winding of the line switch traceable from supervisory ground, through springs 14, through the 115 winding 111, to open main battery. The line switch C being of the preselecting type will always be standing opposite an idle trunk, and, upon the energization of the winding 111, pull-down armature 4 and bridge cut-off armature 5 will be attracted, the former to cause the plunger to enter the bank and the latter to operate the springs 12 and 13 from their respective resting contacts. When the pull-down armature 4 operates, the bank 120 springs of 120, 121, 122 and 123, are forced against their respective bank contacts, extending the circuit to the secondary line switch. The operation of the bridge cut-off armature 5 at springs 12 and 13 opens the 125 130

circuit of the line relay 2, which relay, being slow to release because of the copper collar on its core, remains in an operated position for a few moments after the current is interrupted in its coil.

The operation of the bank terminals extends the circuit to the secondary line switch S which is of the post selecting type in which the wipers have no normal position but move 10 in a forward direction only from the trunk terminals on which they were last used. The operation of the bank springs closes a circuit traceable from ground, through spring 158 and its break contact, conductor 126, bank 15 terminal 123 and its associated bank contact, conductor 101, through the subscriber's telephone loop to conductor 102, to bank terminals 120, conductor 124, through spring 152 and its break contact, through the upper 20 winding of relay 150 to grounded negative battery. Relay 150 energizes over the above traced circuit, but because the upper winding of this relay is comparatively weak the relay energizes only half way; that is, the armatures 204 and 205, shown in Fig. 5, are attracted until the projection of armature 205 strikes the core 209. With the relay in this position springs 154, 155 and 159 make contact with their associated working contacts, 30 but the other springs remain unchanged at this time. The energization of relay 150 in its first step closes a circuit traceable from ground through spring 159 and its make contact, through spring 157 and its break contact, conductor 125, through bank terminals 121, through the winding 110 of the primary line switch C to grounded negative battery. The winding 110 is energized over this circuit and holds the armature 4 of the line switch 40 C in operated position after the winding 111 is deenergized as the relay 2 deenergizes.

The operation of the secondary line switch S from this point depends upon whether or not the trunk upon which the wipers 160, 161 and 162 are standing is busy at the moment. Assume first that it is busy. The wiper 161 will encounter a guarding ground potential, closing a circuit for the motor magnet 151 which is traceable from the ground on the 50 contact encountered by the wiper 161, through spring 153 and its break contact, through spring 155 and its make contact, through springs 159, through the winding of magnet 151 to grounded negative battery. The magnet 151 energizes over this circuit and at springs 159 interrupts its own circuit at the completion of the stroke of the armature. The armature then falls back and advances 60 the wipers 160, 161 and 162 onto the next trunk in the well known manner. If that trunk be busy the circuit for magnet 151 is again closed and the switch operates as before to take another step, continuing this operation until an idle trunk is found. During the trunk hunting operation the lower

winding of the relay 150 is short circuited, having ground potential connected to both of its terminals through spring 155 and its make contact, and through spring 154 and its make contact, the former being grounded 70 from the grounded trunk terminals encountered by the wiper 161 and the latter from the grounded release trunk conductor 125.

When an idle trunk is found no ground potential will be encountered by the test wiper 161 and the short circuit will be removed from the lower winding of relay 150. A circuit will then be closed for this winding traceable from grounded release trunk conductor 125, through spring 154 and its make 80 contact, through the lower winding of relay 150, through springs 159, through the motor magnet 151 to grounded negative battery. The relay 150 energizes over the above traced circuit and pulls the armature 204 of Fig. 5 85 completely against the core, operating the springs 152, 153, 157 and 158 which were not operated upon the first energization of this relay. Magnet 151 is prevented from operating over this circuit by the high resistance 90 of the lower winding of the relay 150. Relay 150, upon energizing, extends the calling line through wipers 161 and 162 to the idle first selector E which switch is seized in the well known manner over conductors 163 and 95 165 and returns the holding ground over conductor 164 to hold the secondary line switch S and the primary line switch C in their energized positions. The first selector E being seized and protected is ready to receive the impulses transmitted by the calling device of the calling station A and operates in response to these impulses to step the wipers 171, 172 and 173 up and around into engagement with the trunk terminals 174, 100 175 and 176 leading to the next switch to be used.

When the conversation is completed and the calling and called parties have replaced their receivers ground is removed from the 110 conductor 164 in the well known manner and the relay 150 and the winding 110 are deenergized allowing the secondary and primary line switches, respectively, to restore to normal.

In the event that another subscriber, not shown, desires to call the station A, he connects with the normal conductors 101', 102' and 104' of the station A in the well known manner, placing a ground upon the conductor 120 104', closing a circuit traceable from this ground, through the conductor 104', conductor 104, through the winding 110 to grounded negative battery. Winding 110, being comparatively weak, is strong enough 125 to energize the core 9 so that the armature 5 is attracted, but not strong enough to energize the core 9 sufficiently to attract the armature 4. The bridge cut-off armature 5, upon being attracted, opens springs 12 and 130

13, disconnecting the line relay 2 and the start ground from the called line. The called station A may then be signalled and conversation may take place over the line conductors in the well known manner.

5 Having thus described my invention what I consider new and desire to have protected by Letters Patent is pointed out in the appended claims.

10 What is claimed is:—

1. In a telephone system, a relay having a pair of armatures, a core for said relay, both of said armatures rotatable about an axis which lies in the same plane as the faces of the armatures which engage the core of the magnet, and a bracket acting as a bearing for both armatures upon which the two are mounted as a unit and which unit is then attached to the relay.

20 2. In a telephone system, a relay having a pair of armatures, a core for said relay, both of said armatures rotatable about an axis which lies in the same plane as the faces of the armatures which engage the core of the magnet, and a bracket acting as a bearing for both armatures upon which the two are mounted as a unit, said unit mounted on said relay in such a manner that the axis lies in the same plane with the face of the core engaged by the armatures.

30 3. In a telephone system, a mounting frame for an automatic switch formed from a single sheet of metal comprising a base having projections forming the heel pieces of the relays of said switch.

40 4. A switch frame comprising a base having projections formed at right angles thereto, the first of said projections forming a mounting plate for mounting said frame, the second projection forming a heel piece upon which are mounted the armature and spring assembly of one of the relays of said switch, a second heel piece formed as a projection of mounting plate and being at right angles thereto and in a plane parallel to the plane of said first heel piece, said frame and projections being of a unitary structure so designed as to permit its being formed from sheet metal stock.

50 5. A switch frame comprising a base, a projection of said base disposed at right angles thereto and forming a mounting plate by means of which said frame may be mounted on a suitable support, a second projection of said base disposed at right angles thereto and at right angles to said mounting plate, a projection of said mounting plate disposed at right angles thereto and parallel to said second projection, said second and third mentioned projections forming heel piece structures for mounting the relay armatures and spring assemblies.

60 6. In a telephone system, a relay heel piece having a magnet core and springs mounted thereon, two armatures for said relay, both

of said armatures rotatable about an axis which lies in the same plane as the faces of the armature which engage said magnet core, and a bracket acting as a bearing for both armatures upon which the two are mounted as a unit and which unit is then attached to said heel piece.

7. In a telephone system, a relay heel piece having a magnet core and springs mounted thereon, two armatures for said relay, both of said armatures rotatable about an axis which lies in the same plane as the faces of the armature which engage said magnet core, and a bracket to which the rod which forms the bearing for both of said armatures is riveted with both armatures rotatably mounted thereon as a unit, which unit is then attached to said heel piece.

In witness whereof, I hereunto subscribe my name this 2d day of March, A. D. 1925.

HERBERT F. OBERGFELL.
